WITNESS:

Patented Feb. 22, 1927.

UNITED STATES PATENT OFFICE.

SIDNEY J. LESTER, OF PRINCETON, KENTUCKY.

BACKBAND HOOK.

Application filed June 20, 1925. Serial No. 38,504.

This invention relates to buckles and slot and one portion thereof will therefore lie above the body member 10 and the other portion beneath the same. The body member 10 is formed to provide spaced upper standing side flanges 14 formed with inclined slots 15 through which are engaged the reduced end portions or tongues 16 of an angular clamping plate 17, which has one edge provided with a plurality of teeth 18 adapted to bite into the back band 60 for maintaining the holding action. The extremities of the tongues 16, that is, outwardly of the side flanges 14 are upset or formed with retaining lips 19 which will prevent the clamping plate from disengagement from the remainder of the device. The back band, of course, passes between the toothed edge 70 of the clamping plate 17 and the intermediate portion of the plate member 10 and it is quite evidenced that when strain is applied 75 to the back band its engagement with the clamping member will tend to slide the latter along the inclined slot 15, this naturally automatically increasing the holding action 80 so that slippage will be positively prevented.

An important object is the provision of a device of this character which is so constructed and arranged that upon slight backward movement of the back band the clamping member will be released so that disengagement of the back band from the device may be very easily effected without being necessary to pry the parts loose as is the case with the ordinary construction.

Another object is the provision of a device of this character having a hook with which a chain or the like may be connected, the hook being so positioned with respect to the back that chafing of the animal will be prevented.

An additional object is the provision of a device of this character which will be simple and inexpensive in manufacture, easy to use and adjust, positive in action, efficient and durable in service, and a general improvement in the art.

With the above and other objects and advantages in view, the invention consists in the details of construction and arrangement of parts to be hereinafter more fully described and claimed, and illustrated in the accompanying drawings, in which:

Figure 1 is perspective view of the device showing it associated with a back band.

Figure 2 is a longitudinal section.

Figure 3 is a detail cross-section taken on the line 3-3 of Figure 2.

Referring more particularly to the drawings, I have shown my device as formed from a single piece of sheet metal which may be cut and bent to shape so it will, of course, be understood that if desired the device could be formed as a casting. The device includes a body portion 10 which is of elongated plate-like formation and which is provided near its ends with slots 11 and 12 and near its central portion with an intermediate slot 13. The back band designated by the letter A is threaded through the

Near the slot 11, the plate or body member 10 is cut as indicated at 20, 21 and 22 and the material within the confines of these cuts is struck out to define a hook 23 upon which a chain or the like may be engaged. The chain will naturally be disposed outwardly of and lie upon the back band so that chafing of the animal will be positively prevented.

From the foregoing description and a study of the drawings it will be apparent that I have thus provided a simply constructed, inexpensive and very easily operated device for the purpose specified which will have the great advantage of increasing its clamping action automatically in accordance with the strain imposed upon it. Furthermore, it is quite evidenced that whenever it is desired to disengage the back band from the device it is merely necessary to ply the former in such a direction as to cause the clamping plate 17 to ride upwardly along the slot 15 whereupon the teeth 18 will be disengaged from the back band permitting the latter to be withdrawn or loosened as the case may be.

While I have shown and described the preferred embodiment of the invention, it should be understood that I reserve the right to make such changes in the form, construc-

tion and arrangement of parts as will not depart from the spirit of the invention or the scope of the subjoined claim.

Having thus described my invention, I claim:

A back band device of the character described comprising an elongated plate-like body member formed at its side edges with spaced upstanding flanges provided with inclined slots, said plate member being provided at intervals with transverse slots

adapted to have a back band threaded therethrough, an angular clamping plate disposed within the said flanges and provided with extensions slideable along said slots, and an out struck hook formed in one end portion of the plate adapted to have a chain engaged thereon.

In testimony whereof I affix my signature.

SIDNEY J. LESTER.
